(57) **CLAIM**

The ornamental design for a refrigerator as shown and described.

DESCRIPTION

FIG. 1 is a front elevation view of a first embodiment of a refrigerator according to our new design;

FIG. 2 is a left side elevation view of the first embodiment of the refrigerator;

FIG. 3 is a right side elevation view of the first embodiment of the refrigerator;

FIG. 4 is a top plan view of the first embodiment of the refrigerator;

FIG. 5 is a bottom plan view of the first embodiment of the refrigerator;

FIG. 6 is a perspective view of the first embodiment of the refrigerator;

FIG. 7 is an enlarged perspective view of portion 7 of the first embodiment of the refrigerator shown in FIG. 6;

FIG. 8 is a front elevation view of a second embodiment of the refrigerator;

FIG. 9 is a left side elevation view of the second embodiment of the refrigerator;

FIG. 10 is a right side elevation view of the second embodiment of the refrigerator;

FIG. 11 is a top plan view of the second embodiment of the refrigerator;

FIG. 12 is a bottom plan view of the second embodiment of the refrigerator;

FIG. 13 is a perspective view of the second embodiment of the refrigerator; and,

FIG. 14 is an enlarged perspective view of portion 14 of the second embodiment of the refrigerator shown in FIG. 13.

(Continued)

The broken lines in the drawings illustrate portions of the refrigerator that form no part of the claimed design.
The dot-dash broken lines surrounding details shown in FIGS. 6, 7, 13 and 14 are for purposes of annotating the enlarged views only and form no part of the claimed design.
